POWER UNIT FOR BLENDERS OR THE LIKE

Dave Chapman and Robert C. Le Sueur, Chicago, Ill., assignors to Scovill Manufacturing Company, Waterbury, Conn., a corporation of Connecticut

Filed June 27, 1962, Ser. No. 70,702

Term of patent 14 years

(Cl. D89—1)

FIG. 1.

FIG. 2.

FIG. 3.

FIG. 4.

FIG. 1 is a side elevational view of a power unit for blenders or the like showing our new design;

FIG. 2 is a rear elevational view;

FIG. 3 is a front elevational view; and

FIG. 4 is a top plan view thereof, on an enlarged scale.

The essential features of the design are shown in full lines on the drawing.

We claim:

The ornamental design for a power unit for blenders or the like, as shown and described.
